United States Patent Office

Des. 220,875
Patented June 8, 1971

220,875

DESIGN FOR AN AUTOMOBILE WINDOW

Friedrich Jochim, Herzogenrath, and Dieter Peetz,
Aachen, Germany, assignors to Compagnie de Saint-
Gobain, Neuilly-sur-Seine, France

Filed Nov. 28, 1967, Ser. No. 9,565

Term of patent 14 years

Int. Cl. D12—14

U.S. Cl. D14—6

FIG. 3.

FIG. 4.

FIG. 8

FIG. 9.

FIG. 11.

FIG. 10.

FIG. 1 is a perspective view of one form of our novel design;

FIG. 2 is a perspective view of a second form of our novel design;

FIG. 3 is a perspective view of a third form of our novel design;

FIG. 4 is a perspective view of a fourth form of our novel design;

FIG. 5 is a sectional elevation view taken along the plane V—V of FIG. 1;

FIG. 6 is a fragmentary sectional view taken along the plane VI—VI of FIG. 2;

FIG. 7 is a fragmentary sectional view taken along the plane VII—VII of FIG. 2;

FIG. 8 is a front elevational view of the design form of FIGS. 1 and 5;

FIG. 9 is a front elevational view of the design form of FIG. 2;

FIG. 10 is a front elevational view of the design form of FIG. 3;

FIG. 11 is a front elevational view of the design form of FIG. 4.

The characteristic features of our invention are the two spaced and mutually-independent bus conductor strips flanking the horizontal elements and extending vertically above and below the latter, together with the shape and location of both the bus conductors and horizontal strips, which are flat and strip-like in nature and disposed on the surface of the window.

We claim:

The ornamental design for an automobile window, substantially as shown and described.
